UNITED STATES PATENT OFFICE.

JOSEPH LEDERER, OF NEW YORK, N. Y.

DESIGN FOR AN INVERTED GAS-LAMP.

No. 38,743.

Specification for Design.

Patented Aug. 6, 1907.

Application filed November 20, 1906. Serial No. 344,352. Term of patent 3½ years.

To all whom it may concern:

Be it known that I, JOSEPH LEDERER, a citizen of the United States, residing at 253 West One Hundred and Twenty-first street, borough of Manhattan, in the county of New York and State of New York, have invented a new, original, and ornamental Design for Inverted Gas-Lamp, of which the following is a specification, reference being had to the accompanying drawing, forming part thereof.

The figure is a plan view of inverted gas lamp showing my new design.

I claim:

The original design for the inverted gas lamp, as shown.

JOSEPH LEDERER.
